US0D1007352S

(12) **United States Design Patent** (10) **Patent No.:** **US D1,007,352 S**
(45) **Date of Patent:** **** Dec. 12, 2023**

(54) **VACUUM GAUGE**

(71) Applicant: **AZBIL CORPORATION**, Tokyo (JP)

(72) Inventors: **Raita Mori**, Chiyoda-ku (JP); **Mayuka Sakai**, Chiyoda-ku (JP); **Takayoshi Kawazu**, Chiyoda-ku (JP); **Satoshi Kamiya**, Chiyoda-ku (JP); **Mitsuhiro Nagata**, Chiyoda-ku (JP); **Yasuhide Yoshikawa**, Chiyoda-ku (JP); **Keisuke Obara**, Chiyoda-ku (JP)

(73) Assignee: **AZBIL CORPORATION**, Tokyo (JP)

(**) Term: **15 Years**

(21) Appl. No.: **29/776,235**

(22) Filed: **Mar. 29, 2021**

(30) **Foreign Application Priority Data**

Oct. 1, 2020 (JP) 2020-021034

(51) **LOC (14) Cl.** **10-04**

(52) **U.S. Cl.**

USPC **D10/85**

(58) **Field of Classification Search**

USPC D10/83, 85, 96; D23/235

CPC G01L 21/00

See application file for complete search history.

(57) **CLAIM**

The ornamental design for a vacuum gauge, as shown and described.

DESCRIPTION

FIG. 1 is a front elevational view of a vacuum gauge showing the new design.

FIG. 2 is a rear elevational view thereof.

FIG. 3 is a top plan view thereof.

FIG. 4 is a bottom plan view thereof.

FIG. 5 is a left side elevational view thereof.

FIG. 6 is a right side elevational view thereof.

FIG. 7 is a front, top, and left side perspective view thereof.

FIG. 8 is a front, top, and right side perspective view thereof.

FIG. 9 is a rear, top, and right side perspective view thereof.

FIG. 10 is a rear, top, and left side perspective view thereof.

FIG. 11 is a front, bottom, and left side perspective view thereof.

FIG. 12 is a front, bottom, and right side perspective view thereof.

FIG. 13 is a rear, bottom, and right side perspective view thereof; and,

FIG. 14 is a rear, bottom, and left side perspective view thereof.

1 Claim, 14 Drawing Sheets
